Patented June 14, 1921.

UNITED STATES PATENT OFFICE.

CHARLES S. BIRD, OF EAST WALPOLE, MASSACHUSETTS.

PAPER-MAKING MACHINE.

1,381,272.

Specification of Letters Patent. Patented June 14, 1921.

Application filed January 10, 1919. Serial No. 270,515.

To all whom it may concern:

Be it known that I, CHARLES S. BIRD, a citizen of the United States, residing at East Walpole, in the county of Norfolk and 5 State of Massachusetts, have invented certain new and useful Improvements in Paper-Making Machines, of which the following is a specification.

This invention pertains to an improved 10 means for cleaning cylinders and felts of paper-making machines, and relates more specifically to an improved form and mounting of the so-called shower pipes.

The main object of the invention is to provide 15 the pipe with a plurality of openings through which water is freed in the form of jets, as such, as contradistinguished from those jets which merge and in effect produce a continuous stream at the point or line of 20 impact thereof with the surface being cleaned. A further object is to impart an endwise reciprocating movement to the pipe whereby the jets are caused to traverse or impact the entire surface of the body to be 25 cleaned, which surface travels past the pipe. Such formation and arrangement of shower pipe while being more effective in operation than those heretofore employed in practice, effects a material saving in the quantity of 30 water necessarily employed and a consequent saving in power used in pumping and forcing the water through the pipes.

Several embodiments of the invention are 35 illustrated in the annexed drawings, where-

Figure 1 is a side elevation of a portion of a flow box and screen with the mounting for the shower pipe and the operating mechanism for reciprocating the same;

Fig. 2 a transverse vertical sectional view;

Fig. 3 a cross section of the pipe and one of the deflectors employed at the end portion of the pipe.

Fig. 4 an elevation of the pipe;

Fig. 5 an elevation of a portion of the pipe on an enlarged scale;

Fig. 6 a cross section of the pipe taken on the line VI—VI of Fig. 5, showing one of 50 the nozzles;

Fig. 7 a side elevation of a modified form of operating mechanism; and

Fig. 8 a view of a felt with the pipes shown in operative relation thereto.

Referring first to Figs. 1 to 6 inclusive, 55 1 denotes the flow box or other fixed part

of a paper-making machine and 2 a revolute screen which is to be cleaned by water passing from the shower pipe. Suitable means such as a clutch driven element 2^a, 60 Fig. 2, is employed to rotate the screen. The pipe is denoted by 3, and is provided with a series of jet nozzles 4. The pipe is mounted for endwise reciprocating movement in suitable bearings 5 and 6, and to one 65 end is secured a flexible hose 7, though any other means of connection with the supply main (not shown) may be employed.

The opposite end of the pipe is closed 70 by a fitting 8 provided with laterally projecting pins 9 which extend into the slotted arms 10 of a yoke-shaped member formed as an extension of the upper arm of a bell crank lever 11. Said lever is fulcrumed on a shaft 12 mounted in fixed brackets 13 and a 75 link or connecting rod 14 connects the outwardly extending arm of the bell crank with a lever 15 secured to a rock shaft 16 to which motion is imparted from any suitable source. 80

From this construction it will be seen that 85 an endwise reciprocating motion will be imparted to the pipe, the motion being at right angles to the movement of the screen surface 2.

The pipe 3 adjacent each end thereof will 90 preferably be provided with deflector plates 17 instead of the nozzles 4, it being found desirable to employ such deflector plates or spreaders at such points as more material is usually brought up by the screen at this end, this by reason of the fact that the screen wire or material adjacent each end overlaps the head of the screen or supporting member for the wire and consequently the material 95 cannot be driven through the wire or removed therefrom at such points as readily as it can be where the wire or screen is not backed up. It is found in practice that the jets issuing from the nozzles if employed at 100 these points tend to form zigzag cuts or lines in the material and it is not removed by such jets as well as it is by the flat thin stream which is produced by the guards 17. Consequently it is advisable to keep such 105 portions constantly under the action of water, which action will be effected by the employment of the deflectors.

The distance between the jet openings in the pipe will be controlled and determined 110 in a measure by the amplitude of reciprocatory movement imparted to the shower

pipe. The greater the movement the farther apart the holes or openings may be spaced. The change in amplitude may be effected by changing the point of connection 5 of the rod 14 to lever 15. Such change may also be effected by the employment of an adjustable throw-crank 18, Fig. 7, driven from a continuously rotating element of the machine, as 19; otherwise the construction 10 is the same as that above set forth.

It is evident that the shower may be employed in conjunction with a felt and such felt is shown in Fig. 8 and designated by 20. Two shower pipes are shown in connection with the felt, one acting upon the outer surface and the other upon the inner surface thereof. The felt 20 passes about rolls as 21 and one or more of them may be driven by any suitable mechanism, as for instance, 20 gearing 22.

By imparting endwise reciprocatory movement to the shower pipe in a horizontal direction and moving the surface to be cleaned at right angles to the longitudinal axis of 25 the pipe, the jets are caused to impinge against the entire surface of the screen or felt and thereby thoroughly cleanse the same. The use of the straight jet, as above noted, effects an impingement of the water against 30 the surface to be cleaned at a greater force or pressure for the same pump pressure, than would be the case where the jet is deflected, as is now commonly done. Consequently, a greater cleaning effect is produced and this 35 with a smaller volume of water.

The term *foraminous* or *foraminous surface* is to be treated in the claims as equivalent of the screen 2 or the felt 20.

What is claimed is:

40 1. In a paper-making machine, the combination of a *foraminous* surface; means for moving the same; a spray pipe provided with a plurality of orifices located adjacent said surface and adapted to eject a cleansing 45 fluid directly against the same; means for imparting endwise movement to said pipe; and means for constantly supplying water to the pipe.

2. In a paper-making machine, the combination of a *foraminous* surface; means for moving the same; a spray pipe located adjacent said surface; a series of unobstructed jet openings formed therein permitting the water to pass directly therefrom and impinge against the *foraminous* surface; means 55 for imparting endwise reciprocatory movement to said pipe; and means for constantly supplying water to the pipe.

3. In a paper-making machine, the combination of a *foraminous* surface; means for

imparting motion thereto; a horizontally disposed spray pipe arranged adjacent said surface, said pipe having a series of unobstructed openings formed therein whereby the jets of water emanating therefrom may 65 directly impinge the *foraminous* surface; means for constantly supplying water to the pipe; and adjustable means for imparting endwise reciprocatory movement to said pipe whereby the amplitude of movement of the 70 pipe may be varied.

4. In a paper-making machine, the combination of a *foraminous* surface; means for moving the same; a spray pipe located adjacent said surface, said pipe having a plurality of openings formed therein; deflectors placed over said openings adjacent each end of the pipe which are in line with the end or marginal portions of the *foraminous* surface; and means for imparting endwise reciprocatory movement to said pipe. 75

5. In a paper-making machine, the combination of a *foraminous* surface; means for moving the same; a perforate spray pipe located adjacent said surface adapted to eject 85 a cleansing fluid directly against the same; means for imparting movement to said pipe at right angles to the direction of movement of the *foraminous* surface; and means for constantly supplying water to the pipe. 90

6. In a paper-making machine, the combination of a *foraminous* surface; means for moving the same; a spray pipe having a series of nozzles carried thereby adapted to eject a cleansing fluid directly against the 95 *foraminous* surface; means for imparting endwise reciprocatory movement to said pipe; and means for constantly supplying water to the pipe.

7. In a paper-making machine, the combination of a screen; means for continuously rotating the same; fixed bearings located adjacent the periphery of said screen; a spray pipe mounted in said bearings and capable of reciprocatory movement therein; a water 105 supply pipe connected to one end of said spray pipe, the opposite end of the spray pipe being closed; an elbow lever fulcrumed on a fixed portion of the machine adjacent said closed end; connections between one 110 arm of the lever and said closed end and connections between the opposite end of the lever and an operative portion of the machine for imparting a rocking motion to said elbow lever and a consequent reciprocation 115 of the pipe.

In testimony whereof I have signed my name to this specification.

CHARLES S. BIRD.
